L. J. SCHMIDT

GAME

Filed Oct. 24, 1924

Loren John Schmidt INVENTOR
Debra G. Haynes BY ATTORNEY

UNITED STATES PATENT OFFICE.

LOREN JOHN SCHMIDT, OF ST. LOUIS, MISSOURI.

GAME.

Application filed October 24, 1924. Serial No. 745,608.

To all whom it may concern:

Be it known that I, LOREN JOHN SCHMIDT, a citizen of the United States, and a resident of St. Louis, Missouri, have invented an improvement in Games, of which the following is a specification.

This invention relates to games, and with regard to certain more specific features, to a game played on a board by any number of persons above one.

Among the several objects of the invention may be noted the provision of a simple and inexpensive game construction adapted for any number of players; and the provision of a novel and attractive game adapted to the requirements of comparatively unskilled players. Other objects will be in part obvious and in part pointed out herein-after.

The invention accordingly comprises the features of construction, combinations of elements and arrangements of parts, which are exemplified in the description herein-after in connection with the accompanying drawings, and the scope of the application of which will be indicated in the following claims.

In the accompanying drawing, in which is illustrated diagrammatically one of various possible embodiments of the invention, the figure represents a plan view of the game unfolded.

Referring now particularly to said drawing, there is illustrated at 1 and 3 a set of plaques composed of a stiff material such as card-board hinged at 5. The hinge 5 may comprise either a score line, cloth hinge or any other suitable hinging means. All of the playing elements are mounted, printed, or otherwise represented on these hinged plaques, and the device is thus adapted to be folded compactly when not in use.

Referring now to the lower plaque 1, there is printed or otherwise illustrated on the right side thereof the likeness 7 of an indicating dial such as is ordinarily used on radio operating panels. This likeness or illustration comprises a circular portion 9 composed of alternate sections 11, and 13

colored black and red respectively. Each set of colored sections, both black and red has its respective portions numbered, preferably according to the some arithmetical progression such as 5, 10, 15 . . . etc., as illustrated here. Each set may have its own progression or use that of the other. The black portions are numbered outwardly of the circle as at 15 and the red portions inwardly thereof as at 17. The dial illustration 7 is provided with a spinning pointer 19 made preferably of metal and loosely pinned to the center of the plaque. Spinner 19 is adapted to rotate loosely and upon being given a rotative motion or spin will come to rest, pointing to any one of the numbered black or red sections as chance may dictate. Beneath the dial illustration is an imitative title 23 indicating that the illustration represents, say, a wave indicator.

To the left of the "wave indicator" is represented another feature found on radio panels i. e., a tuning dial. This illustration comprises a circular disc 25, rotatably pinned to the lower plaque 1 by means of a button 27. This disc 25 is provided with peripheral divisions 29. One half of the divisions 29 are colored black such as at 31 and one half of them are colored red such as at 33. There are equal numbers of black and red divisions on discs 25 and 7 and the divisions on disc 25 are numbered to correspond to numbers on the disc 7. The likeness 35 of a pointer is provided on the plaque 1 and is used as a point up to which a particular numbered division 29 may be brought for a setting.

Underneath the disc 25 and on the plaque 1 are indicated various radio station call letters 37 such as are used for the more important stations in the United States. These call letters are arranged within an annular strip which is concentric with respect to the button 27. In the drawing the disc 25 is broken away to show a group of these call letters. The disc 25 is provided with an open panel 39 through which one set of station call letters may be read at a time. The disc 25 and its allied parts purports to

be a "tuner" as indicated on the plaque at 41. The whole lower plaque is entitled "Receiving set" as shown at 43, and is made to appear realistic with such representations 5 as panel screws 44.

- On the upper plaque 3 is printed or otherwise illustrated a United States map 46 (or map of any district) with the principal broadcasting stations 45 indicated thereon. 10 These stations are indicated by means of their location, the city in which they happen to be located, and their call letters. This data is printed or otherwise illustrated on the map as at 47, 49 and 51, respectively. 15 The call letters on the map correspond to those under the dial 25.

Near the map and printed or otherwise illustrated on the upper plaque 2 is a frame 53 within which is set down the names 55 of 20 the cities shown on the map 43 and opposite each of these names is shown the city's distance 57 from a given city such as St. Louis. The given city is indicated in a title 59 for the frame 53.

- 25 The game is played as follows:

A player spins the pointer 19 which comes to rest, as chance may dictate, pointing either to a black or red section of dial 7 and its corresponding numeral, say forty, 30 red. This, in the spirit of the game gives a wave length.

The "tuner" is then set so that its red section at this number forty is opposite the pointer 35. This puts the panel 39

35 and its aperture over some one of the call letters 37 and the letters may then be read. This, in the spirit of the play, is tuning in on a station.

After the call letters are found, they are 40 located on the map 43, and the city for the corresponding station may be thus ascertained. Then, referring to the frame 53 the distance from this city to a given city such as St. Louis may be read off directly. 45 This distance reading represents the player's score for the one play. His scores per play are added as the play goes on. The players preferably take turns about in spinning.

50 In the present embodiment the black division, one hundred, gives K. S. D. when the "tuner" is set which represents the city of St. Louis and makes the player winner of the game without further play.

55 As many rounds of play as desired may constitute one game.

It will be seen that the game is suited to relatively unskilled players, and during the play any player readily learns the different radio station call numbers, the cities in which such call numbers are located, and the locations of such cities. The game thus includes an educational element while holding the interest of its players. Another 65 advantage of this game lies in the fact

that there are no loose extraneous playing members to become lost and thus the game is relatively more portable than many others.

From the above it will be seen that the 70 several objects of the invention are attained and other advantageous results achieved.

As many modifications of the embodiment above illustrated might be made without departing from the spirit or scope of the present invention, it is intended that the above description and accompanying drawings and claims shall be interpreted as illustrative and not in a limiting sense. 75 80

I claim:

1. A game comprising two hinged plaques, a pointer adapted to be spun and come to rest at a colored and numbered space, a disc with corresponding colored and numbered spaces thereon, a pointer likeness wherewith a setting may be made with said disc, radio station call letters under said disc, an aperture in said disc through which the said call letters are adapted to be read, a map, call letters on said map corresponding to the said call letters, names of cities on said map adapted to be referred to from said call letters, a frame, names of cities in the frame corresponding to the names of the cities on the map and opposite the said names of cities their distances from a given city named in said frame. 90 95

2. A game comprising a pointer adapted to be spun and come to rest pointing to a space, a rotatable disc, spaces corresponding to the above on said disc, means for setting said disc spaces over against another pointer, groups of call letters beneath said disc, an aperture in said disc through which said call-letter groups are adapted to be read, a map, the above named call letters on said map, names of cities on said map corresponding to the stations represented by said call letters, and a reference frame for ascertaining the distances of said cities from a given city. 100 105 110

3. A game comprising a pointer adapted to be spun and to stop giving a reading, 115 means for using this reading to obtain a second and new reading, the above named pointer and means adapted to appear as radio receiving instruments, means for obtaining a third and new reading from the second reading said last named means adapted to appear as a map and a means for obtaining a fourth numerical reading from said third reading, said last named means adapted to appear as a table of city names and corresponding distances, said distances being the player's score. 120 125

4. A game comprising a pointer adapted to be spun and to stop giving a reading, means for using this reading to obtain a 130

second and new reading, the above named pointer and means adapted to appear as radio receiving instruments, means for obtaining a third and new reading from the 5 second reading said last named means adapted to appear as a map and a means for obtaining a fourth numerical reading

from said third reading, said last named means adapted to appear as a table of city names and corresponding distances. 10

In testimony whereof, I have signed my name to this specification this 22nd day of October, 1924.

LOREN JOHN SCHMIDT.
